[57] CLAIM

The ornamental design for a combined computer paper storage and dispensing container, as shown and described.

DESCRIPTION

FIG. 1 is a top perspective view of a combined computer paper storage and dispensing container showing our new design;

FIG. 2 is a top plan thereof;

FIG. 3 is a reduced front elevational view thereof; FIG. 4 is a reduced side elevational view, the opposite side is identical;

FIG. 5 is a reduced scale bottom plan view thereof; and FIG. 6 is a fragmentary enlarged cross section taken in the direction of the arrows on line 6—6 of FIG. 2.
